UNITED STATES PATENT OFFICE.

EMANUEL L. FENSTERMAKER, OF LANCASTER, PENNSYLVANIA, ASSIGNOR
OF ONE-THIRD TO ABRAM H. POWDEN, OF LANCASTER, PENNSYLVANIA.

CAR-BRAKE.

No. 830,476.

Specification of Letters Patent.

Patented Sept. 4, 1906.

Application filed January 21, 1905. Serial No. 242,198.

To all whom it may concern:

Be it known that I, EMANUEL L. FENSTERMAKER, a citizen of the United States, residing at Lancaster, in the county of Lancaster and State of Pennsylvania, have invented certain new and useful Improvements in Car-Brakes, of which the following is a specification.

The object of my said invention is to provide a track-brake for the trucks of cars, particularly street-cars, which may be operated in connection with the wheel-brake and by the same operating power and may be applied with said wheel-brake or after said wheel-brake has been applied or may be disconnected from the operating power, thus providing a track-brake which may be used as a service-brake or as an emergency-brake, all of which will be hereinafter more fully described and claimed.

Referring to the accompanying drawings, which are made a part hereof and on which similar reference characters indicate similar parts, Figure 1 is a top or plan view of a portion of one side of a truck fitted with my improved brake and showing the operating apparatus; Fig. 2, a side elevation thereof as seen when looking in the direction indicated by the arrows from the dotted line 2 2 in Fig. 1; Fig. 3, a view as seen when looking in the direction indicated by the arrows from the dotted line 3 3 in Fig. 1; Fig. 4, a transverse vertical section on the dotted line 4 4 in Fig. 2; Fig. 5, a view similar to a portion of Fig. 2, on an enlarged scale and partly in longitudinal vertical section; Fig. 6, a view looking in the direction indicated by the arrows after the dotted line 6 6 in Fig. 1; Fig. 7, a front view of the shifting lever mounted on the dashboard of the car or in a position convenient for the operator; Fig. 8, a side elevation of the same; Fig. 9, a perspective view of the vertical casing in which the track-brake slides; Fig. 10, a side elevation of one of the wheel-shoes separately, and Fig. 11 a detail sectional view as seen when looking as indicated by the arrows from the dotted line 11 11 in Fig. 5.

In said drawings the portions marked A A' represent the ordinary brake-bars connecting the blocks of the opposite wheel-brakes B B', said blocks, and C the track-brake shoe.

The wheel-brake mechanism is of a well-known construction and arrangement and may be any inside-hung wheel-brake.

The blocks B B' are provided with brake-

shoes b b' of the particular form and arrangement most clearly shown in Fig. 10, the upper end of the shoe being somewhat thicker than at the lower end to compensate for the more rapid wear at the upper part and insure a uniform life for all its parts. Each of said shoes is secured to its respective block by an interlocking rib b³ on one part and a corresponding groove in the other part, each formed with tapered edges and clamped together by a transverse locking-wedge b⁵. A lever 1 is pivoted at 61 to the bar A', and a lever 2 is pivoted at 62 to the bar A, each of said bars being provided with a suitable casting 63 and 64, respectively, at its center for supporting the pivot-bearings.

An adjustable brace comprising a central turnbuckle 60 and end sockets 66 connects the lower ends of said levers 1 and 2, being pivoted thereto by pivots 67 and 68. The top of lever 2 is adapted to rest against the truck-frame beam 65, and the top of lever 1 is connected by rod 3 with the inner end of the "floating" lever 5, which is mounted on the under side of the car and is connected, by means of a link 6, with the lever 7, which is pivoted to the piston 8 of the air-cylinder 9, and also, by means of a link 10, with the lever 11, connected by cable 12 with hand operating power, all as will be presently more fully described. The brake-blocks B B', carrying the bars A and A', are supported, by means of hangers b², from the framework of the truck, as is usual.

The track-brake shoe C is or may be of any suitable construction and is mounted upon the head C' by means of longitudinal ribs r, which engage with corresponding recesses in the opposite corners of the face of the plunger, and transverse ribs r', with tapered edges, which engage with corresponding transverse notches in said plunger. A tapered wedge w with a screw-threaded shank and a nut on its inner end is inserted between one of said ribs and the side of the notch to lock the parts rigidly together. Said head C' is formed with a vertical stem or plunger C², having a bifurcated upper end. A screw-threaded stud c is mounted in a central perforation between the sides of the upper end of said plunger and has an internally-screw-threaded steel thimble c³ mounted thereon. The upper end of said thimble is case-hardened to form a suitable bearing-face for the operating-cam. Channel-bars C³ are securely bolted to each side of brake-block B'

- and extend horizontally nearly across to the opposite brake-block B. The flanges c^1 of said channel-bars are bent at right angles, as shown most clearly in Fig. 4, to form a 5 gib or pocket on the outer face of each bar. A flat bar C⁴ is securely bolted to each side of the brake-block B, and each of said bars is mounted and adapted to slidably fit in one of said pockets. A vertical box or casing 10 C⁵, of the form shown most clearly in Fig. 9, is mounted between said channel-bars c^3 centrally between the wheel-brake shoes riveted or bolted rigidly to said bars. Bearings c^{10} are formed in each side of said casing at its 15 upper end, and a rock-shaft 20 is mounted in said bearings. A cam C⁷ is rigidly mounted on said rock-shaft between the sides of said casing with its cam-face adapted to operate upon the hardened bearing-face on the 20 top of the adjustable thimble c^5 on the stem or plunger C² of the track-brake. A spring 15 of the form most clearly shown in Fig. 5 is secured at one end to one side of the casing C⁵ and engages at its opposite end under 25 an ear c^2 on the top of plunger C². Said spring thus operates to normally hold said plunger and the track-brake carried thereby in an elevated position.
- The rock-shaft 20 is provided with a central crank-arm 21, mounted upon a squared portion thereof. Said crank-arm 21 is connected by the rod 22 with the lower end of the operating-lever 23, which is fulcrumed on a pivot-bolt 24, carried by the outer end 30 of a bar 25, mounted at its inner end on said rock-shaft 20 by means of a strap 26, which encircles said rock-shaft and is bolted to the end of said bar by means of the bolt 27. A spring 28 is connected at one end with the 35 lower end of crank-arm 21 and at the other end with the outer end of bar 25, as shown in Fig. 6 and normally tends to draw said crank-arm toward said point of attachment, and thus operate the cam C⁷ in the opposite 40 direction from that in which it is operated by the application of the power. Thus when said power is released spring 28 contracts, returning said cam and permitting spring 15 to lift said track-brake and the shoe C free 45 from the track. The upper end of operating-lever 23 is connected, by means of rod 29, with the central portion of lever 30, which is pivoted at one end to the frame by pivot 31 and at the other end is connected by a link 50 32 with the floating lever 5. By means of a series of holes h the connection between rod 29 and lever 30 may be made at different points and the desired average or power thus secured. Said floating lever 5 is mounted in 55 suitable brackets 33 on the under side of the car and is held from sliding out of said brackets by means of a short vertical pin 34, inserted through its outer end, thus permitting said bar when not held by the locking 60 device to be presently described to slide

bodily in a horizontal direction back and forth in said supporting-brackets. The locking-lever 35 is mounted upon a pivot 36 in the bracket 37 on the under side of bracket 33. The upper end of said lever extends 70 through a slot in said bracket 33 and is adapted to project across the path of the end of floating lever 5. The lower end of said lever 35 is connected, by means of a rod or cable 38, with the end of a vibrating bar 75 39, which is pivoted in a bracket 40 on the under side of the car. A cable runs from the same end of said vibrating bar over a sheave 42 and is connected to a lever 43, mounted upon a pivot-bolt 44 in a bracket 45, located, 80 preferably, upon the dashboard in front of the motorman. Said cable 41 is connected to a transverse pin 46, carried by said lever 43 in a position which when said lever is thrown upward in the position shown in Fig. 85 8 will bring said pin beyond the center of the pivot on which said lever is mounted, and thus hold said lever in this position. A trip-lever 47 is mounted upon the same pivot 44 and has an extending end 48 adapted to 90 engage behind the pin 46. Its lower end 49 is formed as a foot-lever for the motorman. When it is desired to operate the lever 43 from the position shown by whole lines in Fig. 8 to the position shown by dotted lines, 95 it can be readily done by the operator placing his foot on treadle 49 of said lever 47 and pushing it forward to the position indicated by dotted lines.

It will be understood, of course, that the 100 brake mechanism described is arranged on both sides of the truck, as shown and described for the one side, and also that when the car is provided with two trucks each truck may be similarly equipped. Also that 105 each rock-shaft 20 will have two cams C⁷, one at each end to operate the track-brake on each side of the truck. A connection 50 with the opposite end of a lever 39 will connect with the locking-lever of the other truck, 110 and thus insure that both brake mechanisms, when there are two trucks, will be operated simultaneously.

The operation of the apparatus is as follows: When it is desired to use the track-brake simultaneously with the wheel-brake, 115 the motorman throws lever 43 down, as indicated by dotted lines in Fig. 8, when the spring 51 will draw the connections rearward and throw the lever 35 to the position shown 120 by whole lines in Fig. 3, permitting floating lever 5 to slide freely at both ends. The power being applied either by the hand operating mechanism or the air-cylinder, said lever 5 is drawn toward the front of the car, 125 as indicated by the arrow in Fig. 1, which operates to throw the wheel-brakes against the wheels, and lever 23 operates to turn shaft 20 and throw cam C⁷ against the bearing-face c^5 of the plunger C² and force the track- 130

brake against the track. The force used in the application of said track-brake reacts directly against the wheel-brakes, which are connected therewith through the bars C³ and C⁴, and forces them upwardly against the wheels, and thus all of the force exerted is applied to the rails with a lifting power against the wheels assisting in the stopping of the car instead of reacting against the truck-frame, as is usual in track-brakes. When it is desired that the track-brakes shall remain idle, lever 43 is elevated, as shown by whole lines in Fig. 8, which throws lever 35 into the vertical position, (indicated by dotted lines in Fig. 3,) and thus locks the end of lever 5 behind the upper end of said lever 35, and prevents the movement of said end of said lever when the power is applied, thus operating the opposite end of said lever 5 and the wheel-brake only. When the power is released, lever 5 will be drawn to the rear end of the supporting-strap of bracket 33, passing beyond the end of lever 35, even though it should happen to be in a vertical position, in which case the force of said lever will throw lever 35 to an inclined position (indicated by dotted lines in Fig. 3) and permit the ends of floating lever 5 to pass over it. By this arrangement track-brakes are provided that are rigidly supported in connection with the wheel-brakes, and which when applied react against said wheel-brakes and throw them with great lifting force against the wheels, thus serving to decrease the weight supported by said wheels on the rails, so that should the wheels become locked they will not wear and flatten so rapidly by sliding on the rails, part of the weight of the car being thrown upon the track-shoes. Great efficiency in the operation of the brake is thus secured and the life of the wheels, the wheel-shoes, and the whole apparatus prolonged. When the track-brake is not needed, it may be thrown out of operation very quickly and easily, as above described.

45 By the particular arrangement for securing the track-shoes to the plungers and the wheel-shoes to the blocks great rigidity is secured between the parts, and by the particular form of wheel-shoe with a thickened upper 50 end a shoe is provided that will wear to an even thickness throughout its length and its life be thus prolonged.

Having thus fully described my said invention, what I claim as new, and desire to secure by Letters Patent, is—

55 1. A track-brake for car-trucks comprising a track-shoe mounted upon a vertically-sliding part, which part is mounted in a frame supported by the wheel-brakes, operating mechanism for said track-brake, operating mechanism for said wheel-brakes, power-applying means connected with both sets of operating mechanism, the connection with the track-brake being arranged to be made oper-

ative or inoperative at will, substantially as 65 described and for the purposes set forth.

2. A track-brake for car-trucks mounted in a support carried upon a frame secured to the shoes of the wheel-brake, a single brake-applying lever, and devices for operating said track-brake and wheel-brakes connected with said lever, said devices being arranged to operate said wheel-brake independently of or simultaneously with said track-brake, substantially as set forth. 75

3. The combination, of the wheel-brakes of the car-truck supported adjacent to the under side of the wheels, a horizontally-extensible frame carried by said wheel-brakes, a vertical casing carried by said frame, a track-brake the stem or plunger whereof is mounted to slide in said casing, and means for operating said stem or plunger vertically in said casing, said means being connected with the wheel-brake-operating mechanism, whereby 85 said brakes may be operated simultaneously and the application of said track-brakes will also force said wheel-brakes upwardly against the under side of the wheels with greater power, substantially as set forth. 90

4. The combination of the wheel-brakes of the car-truck mounted between the adjacent sides of the wheels and supported to move toward and from said wheels, a horizontal frame composed of bars secured to the blocks 95 of said wheel-brakes and engaged with each other to slide and form an extensible frame, a vertical casing mounted between said bars, a track-brake formed with a suitable stem or plunger mounted to slide in said casing, means for normally holding said track-brake in an elevated position, a cam mounted upon a rock-shaft engaging with said plunger for forcing the said track-brake downward, and means for operating said rock-shaft, substantially as set forth. 100 105

5. The combination of the wheel-brake, means for operating said wheel-brake, the track-brake, means for operating said track-brake, a floating lever connected at one end 110 with a means for operating the wheel-brake and at the other end with a means for operating the track-brake, an intermediate connection with the operating power, and means for locking the end of said lever connected 115 with the track-brake-operating mechanism in a fixed position and releasing it when desired, substantially as set forth.

6. The combination of a wheel-brake, the operating mechanism for said wheel-brake, a 120 track-brake, the operating mechanism for said track-brake, a floating lever connected at one end with the actuating-lever of the wheel-brake-operating mechanism, and near the other end with the actuating-lever of the 125 track-brake-operating mechanism and connected at an intermediate point with the power, a locking-lever adapted to engage the

end of the floating lever with which the track-brake-operating mechanism is connected and hold it in a fixed position when desired, and a connection running from said lever to a position convenient to the motorman and connected with an operating-lever, whereby said motorman may operate said locking-lever as desired, substantially as set forth.

7. The combination in a brake mechanism for car-trucks, of the wheel-brakes hung between the wheels of the truck upon suitable supports, an extensible frame connecting the blocks of said wheel-brakes, a vertical casing carried by said frame, a track-brake the plunger whereof is mounted in said casing, a rock-shaft journaled in bearings in the upper end of said casing, a cam rigidly mounted on said rock-shaft between the sides of said casing and adapted to engage with the bearing-face of said plunger, means for normally holding said track-brake elevated, and means con-

nected with suitable power for operating said rock-shaft to depress said track-brake when desired, substantially as set forth.

8. In a brake mechanism for car-trucks, the combination of the wheel-brakes, means for operating said wheel-brakes, the track-brake, means for operating said track-brake, a floating lever connected with the means for operating both of said brakes and with the operating power, and means for rendering the end of said lever connected with the track-brake mechanism active or inactive, as desired, substantially as set forth.

In witness whereof I have hereunto set my hand and seal, at Lancaster, Pennsylvania, this 24th day of December, A. D. 1904.
